UNITED STATES PATENT OFFICE.

JOHN D. MADDEN, OF FALL RIVER, MASSACHUSETTS.

STAMP-VENDING MACHINE.

1,268,372.

Specification of Letters Patent. Patented June 4, 1918.

Application filed June 26, 1917. Serial No. 177,050.

To all whom it may concern:

Be it known that I, JOHN D. MADDEN, a citizen of the United States, residing at Fall River, in the county of Bristol, State of Massachusetts, have invented a new and useful Stamp-Vending Machine; and I do hereby declare the following to be a full, clear, and exact description of the invention, such as will enable others skilled in the art 10 to which it appertains to make and use the same.

The present invention relates to a stamp vending machine, and has for its object to provide a device of this character which 15 embodies novel features of construction whereby a stamp will be ejected when it is manipulated after inserting the necessary coin or coins into the machine.

Further objects of the invention are to 20 provide a stamp vending machine which is comparatively simple and inexpensive in its construction, which can be easily operated, which will not eject a stamp until after the necessary coin has been inserted in the slot, 25 and which handles the stamps without danger of mutilating or injuring the same.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following 35 description and accompanying drawings, in which:—

Figure 1 is a horizontal sectional view through a stamp vending machine constructed in accordance with the invention.

Fig. 2 is a longitudinal vertical sectional view through the machine, on the line 2—2 of Fig. 1.

Fig. 3 is an enlarged detail view of the lower end of the vertically reciprocating plunger, together with parts associated therewith, being a section on the line 3—3 of Fig. 1.

Fig. 4 is a similar view of the upper end of the plunger, looking at the same from a 50 position at right angles to that of Fig. 3.

Fig. 5 is a detail view of the trip means which co-operates with the main operating lever to release the coin, when the machine is actuated.

Corresponding and like parts are referred

to in the following description and indicated in all the views of the drawings by the same reference characters.

Referring to the drawings, the reference character A designates a base upon which the mechanism is mounted, and B an inclosing casing. A vertically disposed operating plunger 1 extends upwardly from the base A, being provided at its lower end with a stem 1^a which is slidably mounted within a guide sleeve 1^b projecting from the base. A coil spring 2 surrounds the stem 1^a and bears against the shoulder at the upper end of the stem 1^a to hold the plunger normally at the upper limit of its movement. The stamp ejecting mechanism is constructed and arranged to be operated by the vertical movements of the plunger 1, as will be hereafter described. The upper end of the plunger 1 is bifurcated and has the main operating lever 3 pivotally mounted within the bifurcation, the outer end of the lever being provided with a suitable finger-piece 3^a for convenience in manipulating the same, while the inner end thereof is normally in engagement with the weighted slide 4 which is mounted within the vertical guides 5. The handle 3^a of the operating lever is weighted at 3^b so as to hold the other end of the lever in a loose engagement with the weight 4. The inner end of the lever 3 is mounted to swing between the two complementary halves 6 of a slotted coin guide, the upper end of the coin guide being pivotally connected at 7 to the upper end of the plunger 1, while the lower end of the coin guide is hingedly connected at 8 to a cross head 9 which slides back and forth in substantially horizontally disposed guideways 10. The inner edges of the complementary members 6 are grooved or slotted at 6^a to receive a coin C which when in operative position spans the space between the members 6 and extends across the path of the inner end of the operating lever 3. The grooved edges of the complementary halves 6 of the guide member are cut away at their lower ends, as indicated at 11, to provide for the discharge or release of the coin after the machine has been actuated. In a similar manner, the grooved edges of the members 6 are cut away at the upper ends thereof, as indicated at 12, and pivotally connected at 13 to the lower end of a coin chute 14, said chute being formed in two sections which 110

telescope over each other at 14^a, the upper section of the chute opening through the exterior of the casing B so that a coin can readily be inserted into the same, while the lower member is curved and arranged to deflect the coin into the grooved edges 6^a of the coin guide arm or lever 6. The upper edge of the main lever 3 is provided with a coin stop 15 which normally projects between the complementary members 6 of the coin guide lever to engage a coin and arrest the movement thereof before it reaches the lower end of the member 6 and is discharged through the cut-away portion 11 thereof.

With the coin in position in the coin guide lever 6 and engaged by the coin stop 15 of the main lever 3, it will be obvious that if the finger-piece 3^a at the outer end of the main lever is forced downwardly the inner end of the lever will be held in a firm engagement with the coin C so that the plunger 1 will be moved downwardly against the action of the coil spring 2. Upon the release of the finger-piece the tension of the coil spring 2 will move the vertical plunger 1 up to its original position. If an attempt is made to actuate the machine without first inserting the necessary coin or coins in the slot, the inner end of the main lever 3 will merely swing upwardly between the complementary halves of the coin guide arm 6, lifting the weighted slide 4, and the vertical plunger 1 will not be forced downwardly by the manipulation of the handle 3^a.

Projecting laterally from one side of the plunger 1 is a stub shaft 16 upon which a pair of oppositely facing pawls 17 and 18 are mounted. The pawl 17 is arranged for engagement with the ratchet wheel 19 of a horizontal shaft 20 to rotate the said shaft on the downward movement of the plunger, while the pawl 18 is arranged for engagement with the ratchet wheel 21 of a second horizontal shaft 22 to rotate the said shaft on the return movement of the plunger. The two shafts 20 and 22 are arranged in a horizontal plane on opposite sides of the plunger 1 and have a parallel relation to each other, the ends of the shafts being shown as journaled within suitable supports 23.

The shaft 20 is provided with a polygonal feed block 24, said block being shown in the present instance as being rectangular in shape, and each face of the block being the exact size and configuration of a single postage stamp. This block unrolls the stamps in strip form from a supply roll 25, drawing them through suitable tension rollers 26. The edges of the feed block 24 are preferably formed with teeth 27 for engagement with the perforations between the stamps. The opposite horizontal shaft 22 is provided with a stamp discharge block 29

which is similar in shape to the feed block 24 and is arranged at one side thereof, the two blocks being properly spaced to clear each other as they are rotated, and to provide the necessary clearance for a cutting blade 30 which is utilized to sever the stamps from the strip before they are discharged from the machine. A pair of stripping fingers 28 project upwardly between the two stamp feeding blocks 24 and 29, said stripping fingers being carried by a shaft 28^a and normally held by the action of a spring 28^b in a yielding engagement with grooves 28^c extending peripherally around the block 24. The upper ends of the stripping fingers 28 terminate substantially flush with the upper faces of the blocks and assist in guiding the end of the stamp strip across the space between the blocks. These stripping fingers will also prevent the stamps from sticking to the feed block 24 and being carried around with the same, instead of directed over upon the discharge block 29. A spring pressed roller 31 may be provided for successive engagement with the notches or depressions in an end plate 32 applied to each of the blocks 24 and 29 for the purpose of bringing the blocks to rest at all times with the upper faces thereof horizontally disposed.

Upon the downward movement of the plunger 1 the pawl 17, as previously described, will engage the ratchet wheel 19 and rotate the horizontal shaft 20 and feed block 24 substantially a one-quarter revolution, thereby moving the stamp at the end of the strip over upon the upper face of the stamp discharge block 29. A continued downward movement of the vertical plunger 1 brings spring mounted presser blocks 33 into a yielding engagement with the top of the blocks 24 and 29, thereby holding the stamps securely in engagement therewith. While the stamps are thus held firmly in position, the slotted end 34^a of a link 34 which is pivotally connected to a lug 35 projecting laterally from the plunger 1 engages the pin 36 of the cutting blade 30 and swings the latter downwardly into operative position, thereby severing the stamp which was previously fed to the discharge block 29 from the end of the stamp strip. This cutting blade 30 is shown as carried by a horizontal shaft 37 which is arranged transversely above the shafts 20 and 22 and is mounted upon suitable supports 38. Upon the return movement of the plunger 1 the presser blocks 33 are raised into inoperative position and the pawl 18 brought into engagement with the ratchet wheel 21 of the horizontal shaft 22 to rotate the block 29 and discharge the stamp which was previously separated from the end of the strip by the cutting blade, said stamp dropping into a suitable box or receptacle 39 from which it

can be easily withdrawn. The presser blocks 33 may be slidably mounted upon the vertically disposed outer ends of brackets 40 which project laterally from the plunger 1, upward movement of the presser blocks 5 being resisted by springs 41.

The inner arm of the main operating lever 3 is provided at an intermediate point in its length with a downwardly extending inclined latch arm 42 which is adapted to be engaged by one of the arms of an elbow shaped latch lever 43 to hold the inner arm of the operating lever depressed during the return movement of the plunger. This latch 10 lever 43 is suitably mounted upon a shaft 44 and the vertical arm thereof is engaged by a spring 45 which normally holds it in operative position, although it can swing against the action of the spring to become engaged 15 with the latch member 42 or disengaged therefrom. During the initial portion of the return movement of the plunger 1 the inner arm of the main operating lever 3 is held depressed by the latch lever 43, thereby 20 by withdrawing the coin stop 15 from the path of the coin through the coin guide arm 6 and permitting the coin which was previously in position within the guide arm to slide to the lower end thereof and be discharged through the cut away portion 12 25 thereof. When the vertical plunger 1 reaches the limit of its return movement the latch arm 42 becomes forcibly disengaged from the latch lever 43 so that the main lever swings back to its original position 30 with the end thereof in engagement with the weighted slide 4 and the coin stop 15 thereof projecting between the two complementary halves of the coin guide arm 6. The mechanism 35 is thus in position to eject another stamp if a coin is inserted in the slot and the operating lever manipulated. If it is desired to provide for ejecting a stamp when two coins are inserted in the slot, the cut 40 away portion 11 at the lower end of the coin guide lever 6 can be extended farther along the upper halves of the grooved edges of the guide lever, so that the first coin deposited in the machine will merely serve as 45 a stop to hold the second coin in operative position, and if the lever is manipulated without inserting a second coin, the first coin will merely be unseated from the guide lever and ejected without operating the 50 stamp feeding mechanism.

Having thus described the invention, what I claim as new and desire to secure by Letters Patent, is:—

1. A stamp vending machine including a 55 vertically reciprocating plunger, means for operating the plunger, a pair of horizontally disposed shafts arranged adjacent to the plunger, a stamp feeding block on one of the shafts, a complementary stamp ejecting block 60 on the other shaft, means for guiding a strip

of stamps to the feeding block, means actuated by the downward movement of the plunger to turn the feeding block and move the end of the stamp strip over upon the ejecting block, cutting means for severing 70 the end of the stamp strip, and means actuated by the return movement of the plunger for turning the discharge block to eject the severed stamp.

2. A stamp vending machine including a 75 vertically reciprocating plunger, means for operating the plunger, a pair of horizontally disposed shafts arranged adjacent the plunger, a stamp feeding block on one of the shafts, a complementary stamp ejecting block 80 on the other shaft, means for guiding a strip of stamps to the feeding block, ratchets upon the respective shafts, a pawl carried by the plunger for engagement with one of the ratchets to rotate the shaft of the stamp feeding block and move the end of the stamp strip over upon the ejecting block on the downward movement of the plunger, cutting means for severing the end of the stamp strip, a second pawl carried by the plunger 85 for engagement with the other ratchet on the return movement of the plunger to rotate the ejecting block and discharge the severed stamp. 90

3. A stamp vending machine including a 95 vertically reciprocating plunger, means for operating the plunger, a pair of horizontally disposed shafts arranged adjacent the plunger, a stamp feeding block on one of the shafts, a complementary stamp ejecting block 100 on the other shaft, said blocks being formed with square faces to receive the stamps, means for guiding a strip of stamps to the feeding block, means actuated by the downward movement of the plunger to turn the feeding block and move the end of the stamp strip over upon the ejecting block, presser means carried by the plunger and mounted to be brought into engagement with the stamps to hold them against the faces of the 105 blocks, cutting means actuated by the plunger for severing the end of the stamp strip while it is clamped in position by the presser means, and means actuated by the return movement of the plunger for turning the 110 ejecting block to discharge the severed stamp. 115

4. A stamp vending machine including a vertically reciprocating plunger, means for operating the plunger, a pair of horizontally disposed shafts arranged adjacent to the plunger, a stamp feeding block on one of the shafts, a complementary stamp ejecting block on the other shaft, said blocks being formed with square faces to receive the stamps, means for guiding a strip of stamps 120 to the feeding block, means actuated by the downward movement of the plunger to turn the feeding block and move the end of the stamp strip over upon the ejecting block, a pair of spring actuated presser blocks car- 125 130

ried by the plunger and mounted to yieldably engage the square faces of the blocks to hold the stamps in engagement therewith, cutting means actuated by the plunger for severing the end of the stamp strip while it is engaged by the presser blocks, and means actuated by the return movement of the plunger for rotating the ejecting block to discharge the severed stamp.

10. 5. A stamp vending machine including a vertically reciprocating plunger, means for operating the plunger, a pair of horizontally disposed shafts arranged adjacent the plunger, a stamp feeding block on one of the shafts, a complementary stamp ejecting block on the other shaft, said blocks being formed with square faces to receive the stamps, means for guiding a strip of stamps to the feeding block, ratchets upon the respective shafts, a pawl carried by the plunger for engagement with one of the ratchets to rotate the shaft of the stamp feeding block and move the end of the stamp strip over upon the ejecting block on the downward movement of the plunger, spring actuated presser blocks carried by the plunger and mounted to bear yieldably against the square faces of the blocks to hold the stamps in engagement therewith, cutting means actuated by the plunger for severing the end of the stamp strip while it is engaged by the presser blocks, and a second pawl carried by the plunger for engagement with the other ratchet to rotate the ejecting block and discharge the severed stamp on the return movement of the plunger.

6. A stamp vending machine including a vertically reciprocating plunger, means for operating the plunger, a pair of horizontally disposed and parallel shafts arranged on opposite sides of the plunger, a stamp feeding block on one of the shafts, a complementary stamp ejecting block on the other shaft, means for guiding a strip of stamps to the feeding block, means actuated by the downward movement of the plunger to turn the feeding block and move the end of the stamp strip over upon the ejecting block, a third shaft extending transversely of the

parallel shafts, a swinging knife blade mounted upon the third shaft and arranged to swing between the two blocks to sever the end of the stamp strip, a link connection between the knife blade and the plunger for actuating the knife blade after the feed block has been turned, and means actuated by the return movement of the plunger for rotating the ejecting block to discharge the severed stamp.

7. A stamp vending machine including a vertically reciprocating plunger, means for operating the plunger, a pair of horizontally disposed parallel shafts arranged on opposite sides of the plunger, a stamp feeding block on one of the shafts, a stamp ejecting block on the other shaft, said blocks being formed with square faces adapted to receive the stamps, ratchets upon the respective parallel shafts, a pawl carried by the plunger for engaging one of the ratchets to rotate the shaft of the stamp feeding block and move the end of a stamp strip over upon the ejecting block on the initial downward movement of the plunger, presser blocks carried by the plunger and arranged to bear against the square faces of the blocks to hold the stamp strip in a firm engagement therewith after the actuation of the feed block, a third shaft extending transversely of the parallel shafts, a knife blade mounted upon the third shaft to swing between the blocks and sever the end of the stamp strip, a link connection between the knife blade and the plunger for actuating the knife blade when the plunger reaches the lower limit of its movement, and a second pawl carried by the plunger for engagement with the other ratchet to rotate the ejecting block and discharge the severed stamp on the return movement of the plunger.

In testimony whereof I have signed my name to this specification in the presence of two subscribing witnesses.

JOHN D. MADDEN.
